(57) **CLAIM**

The ornamental design for a wireless transmitting and receiving module, as shown and described.

DESCRIPTION

FIG. 1 is a front, top and left-side perspective view of a wireless transmitting and receiving module showing our new design;

FIG. 2 is a bottom perspective view thereof;

FIG. 3 is another bottom perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof;

FIG. 9 is a bottom plan view thereof;

FIG. 10 is an enlarged view of area **10** indicated by the two dot-dash broken lines in FIG. 1; and,

FIG. 11 is an enlarged view of area **11** indicated by the two dot-dash broken lines in FIG. 2.

The broken lines depict portions of the wireless transmitting and receiving module that are shown for environmental purposes only and form no part of the claimed design. The dot-dash broken lines define the boundary of the claimed design and form no part of the claimed design. The rectangle indicated by the two dot-dash broken line shown in each of FIG. 1 and FIG. 2 illustrates the boundaries of an enlarged area of the design. The “**10**”, “**11**” indicia and splined curve indicated by the two dot-dash broken line in each of FIG. 1 and FIG. 2 identifies each enlarged area. None of the broken lines form any part of the claimed design.
